UNITED STATES PATENT OFFICE.

GIOVANNI EMANUELE ELIA, OF ROME, ITALY.

SUBMARINE MINE.

1,096,698.

Specification of Letters Patent. Patented May 12, 1914.

Application filed May 21, 1913. Serial No. 768,931.

To all whom it may concern:

Be it known that I, GIOVANNI EMANUELE ELIA, a subject of the King of Italy, and a resident of Rome, Italy, have invented a new and Improved Submarine Mine, of which the following is a full, clear, and exact description.

This invention relates to submarine mines, and more particularly to floating mines of that type which are adapted to be moored around or in the course of an enemy's ship or fleet when the location or course of such ship or fleet is discovered, so that when the mines are encountered the ship or ships striking the same will be destroyed or thrown out of commission.

An object of the invention is to provide a floating cable having mines suspended on the ends thereof so that the cable by floating on the surface of the water will, upon being struck by the bow of a ship, be dragged along with the latter so as to cause the mines suspended on the ends of the cable to be drawn inwardly to and finally into contact with opposite sides of the hull of the ship when the mines are exploded with the effect of destroying or throwing the ship out of commission.

Another object of the invention is the use in connection with mines at the ends of the floating cable of mine anchors that are suspended from the mines so as to cause the same to occupy a proper relation to the hull of the ship or point below the armor thereof, said mine and anchor being normally tied together and adapted to be automatically released by a device controlled by a drag anchor when the floating cable with the mines on the ends thereof is caught up and carried along by a moving vessel, whereby the resistance of the drag anchors will cause cables to unwind until they are a suitable distance behind the mine anchors, when the mine anchors will be automatically untied from the mines, allowing the mine anchors to depend from the mines, and also allowing the mines to assume an upright position and causing the firing means to explode the mines.

With these objects in view, and others as will appear as the description proceeds, the invention comprises various novel features of construction and arrangement of parts which will be more fully described herein-

after and set forth with particularity in the 55 claims appended hereto.

In the accompanying drawings, which illustrate one embodiment of the invention, and wherein similar reference characters are employed to designate corresponding 60 parts throughout the several views, Figure 1 is a side view of one of the mines or bombs and its associated instrumentalities that are connected to one end of the floating cable; Fig. 2 is a side view of the parts shown in 65 Fig. 1; Fig. 3 is a view showing a mine just after it has been placed in the water; Fig. 4 is a view showing the mine sunk to the normal depth and with the mine anchor still attached to the mine; Fig. 5 shows the 70 mine anchor released and suspended from the mine or bomb and with the drag anchor paying out from the mine anchor; Fig. 6 is a view showing the final position of the mine and its attached parts when firing 75 takes place; and Figs. 7 to 9 inclusive are diagrammatic views showing the manner in which a ship encounters the floating cable and causes the mines suspended on the ends of the cable to be brought into engagement 80 with the sides of the ship.

Referring to the drawings, A designates the mines or bombs, B the suspending cable for each bomb, C the floating cable, D the mine anchors, E the suspending cables or 85 lines for the mine anchors, F the drag anchors, G the line for each drag anchor, H the winding drums for the lines G, I the retaining cable or element for normally securing each mine to its anchor, and J the 90 releasing mechanism between each winding drum H and retaining cable I, whereby the mine anchor is detached and dropped from its mine and allowed to assume a suspending position while the mine itself assumes an up- 95 right position suitable for firing.

The mine A is of any suitable construction and is provided with a firing device 1 which is controlled by breakable wires 2 that are engaged with the lower section 3 of the 100 mine suspending cable B, so that when a strain of sufficient power is brought to bear on the suspending cable the breakable wires 2 will break successively and finally cause the bomb or mine to be exploded by the 105 firing device 1 as further described. The section 3 of the suspending mine cable B is attached by an eye or equivalent device 4 to

the mine A, and the other end of the section 3 is connected with a ring 5 to which the section 6 of the mine cable B is fastened. The upper end of the mine cable B is connected with a buoy 7 fastened to the end of the floating cable C, such cable C having spaced along its length small floats 8 whereby the cable C will float on the surface of the water so as to be encountered by a moving ship.

The mine anchor D is a body of metal or other suitable material of rectangular or any other suitable shape and serving normally to form a carriage for the mine A, there being wheels 9 on the bottom of the anchor D, so that it, with the mine, can be conveniently wheeled about, and the top of the anchor has a cavity or seat 10 in which the mine B rests on its side, as clearly shown in Figs. 1 and 2, the suspending eye 4 being at what is properly the top of the mine. The anchor D is adapted to be suspended from the bottom 11 of the mine A by a cable E which has at its upper end a swivel connecting device 12 of suitable construction that is attached to the eye 13 fastened centrally to the bottom of the mine. The anchor suspending cable E, which is normally coiled in the anchor, has its lower end suitably secured to the latter.

The drag anchor F is of usual construction and consists of a cone 14 of canvas or other suitable material with its open end fastened to a ring 15 from which extends a plurality of wires or equivalent members 16 that are united with a ring 17 to which is attached the drag anchor cable G. The drag anchor is normally suspended on a catch or hook 18 fastened to the side of the mine anchor D, such hook 18 engaging in the ring 17, and from this ring 17 the cable G, as shown in Fig. 2, passes over a guide pulley 19 on the mine anchor D and thence winds around the drum H fixed to a shaft 20 journaled in bearings 21 at one of the adjacent sides of the anchor D. When the floating cable C is caught up by a moving vessel a drag is produced on the mines at the end of the floating cable and the parts associated with the mines, and consequently the drag anchors F are caused to change from a pendent to a horizontal position, whereby the rings 17 release from the hooks 18 and consequently the drums 12 will unwind under the greater drag or pulling power of the drag anchors F until the cables G are paid out. The means for retaining the mine A on its main anchor D consists of a cable or line I which is fastened at 22 to one side of the anchor D and extends upwardly and over the mine A and thence downwardly to the opposite side of the anchor D, where the hook 23 or equivalent device is engaged with a sliding bolt 24 mounted on the anchor D. This retaining cable I

not only holds the mine A seated fast on the anchor D, but by passing through the ring 5 of the mine suspending cable B, the weight of the mine and attached parts is relieved from the section 3 of the suspending cable B, so that the firing mechanism of the mine cannot be brought into play until the mine is properly suspended for that purpose.

The mechanism J for releasing the retaining cable I so that the mine and its anchor can separate and the latter be suspended from the former, comprises a worm 25 on the shaft 20 which meshes with a worm wheel 26 rotatably mounted on the anchor D, and in the hub 27 of the gear wheel 26 is a recess 28 into which the end 29 of the bolt 24 is adapted to spring when the wheel has revolved a sufficient distance, the bolts 24 being acted on by a spring 30 which tends to urge the bolt toward the right, Fig. 1, and when the recess 28 alines with the bolt the latter moves to the right and disengages the end 31 of the bolt from the hook or catch 23 on the retaining cable or element I.

Assuming that the floating cable C is about six hundred feet in length, with the mines or bombs applied to the end thereof and suspended about nine feet below the surface of the water; the drag anchor cables G will be about four hundred feet in length, and when they have unwound from their drums to this length the catch-holding bolts 24 are released so that the retaining cables I will allow the main anchors D to drop from the mines A and hang therefrom a distance of ten or twenty feet, and simultaneously with the dropping of the anchors D the mines A will assume an upright position.

If the location of an enemy's ship or fleet is known and it is desired to hem the enemy in with submarine mines of the character referred to, a fleet of mine planters will plant the mines in a circle having a radius beyond the range of the enemy's guns, the floating cables C being laid end to end in a more or less continuous circle around the enemy's fleet, or they may be arranged in a straight line across the course which the enemy's fleet is taking. In planting submarine mines the mine A and its attached parts are lowered into the water as shown in Fig. 3, with the cable C and buoy 7 floating, and as the mine sinks the section 6 of the suspending cable B straightens out from the position shown in Fig. 3 to that shown in Fig. 4. The mines on the ends of the cable remain in this position until the floating cable C is caught on a moving vessel in a manner more or less as shown in Fig. 7, wherein S represents diagrammatically a battleship approaching the floating mine. The floating cable C is dragged along with the vessel and the mines A suspended on the ends are caused to move inwardly simultaneously to-

ward the sides of the vessel, and coincident with the drag on the floating cable C the drag anchors F are released from the mine anchors and the drag anchor cables paid out, as shown in Fig. 8. By the time the drag anchor cables are fully paid out the mines are in contact with or adjacent the sides of the hull of the ship and suspended in the region of the vulnerable part thereof, that is, below the armor line. At the time the drag anchor cables are fully unwound, the anchor retaining device I is released so that the anchor D will drop from the mine and exert a pull thereon, the mine in the meantime assuming an upright position, and finally when the pull exerted by the anchor D is sufficiently strong it will cause the wires 2 to successively break. The breaking of the wires 2 releases a spring (not shown on the drawings) adapted to the mechanism of percussion; the releasing of this spring enables the striker to come into action; consequently the mine will explode and destroy or cripple the battleship. The mines explode practically simultaneously and at opposite sides of the battleship so as to have a maximum destroying effect. The ship may not strike the floating cable directly in the center, as shown in diagrams Figs. 7 to 9 inclusive, but nearer to one end than the other, but even so the operation will be the same, that is to say, the mines will come into contact with the hull of the boat at opposite sides, one nearer the bow than the other, but the explosions will take place at opposite sides of the hull.

From the foregoing description taken in connection with the accompanying drawings, the advantages of the method of operation and of the apparatus shown will be readily understood by those skilled in the art to which the invention appertains, and while I have described the apparatus which I now consider to be the best embodiment thereof, I desire to have it understood that the apparatus shown is merely illustrative and that such changes may be made when desired as are within the scope of the appended claims.

Having thus described my invention, I claim as new and desire to secure by Letters Patent:

1. A submarine mine comprising a float, a suspending element connected therewith, an explosive body having connection with the said element, a main anchor, means for releasably connecting the anchor and body together, a releasing device for said connecting means, a drag anchor for controlling the said device for releasing the anchor from the body, a flexible element for suspending, when released, the anchor from the body, and a firing means actuated after the releasing of the anchor from the body and by the suspension of the anchor on the body.

2. A submarine mine comprising a float, a mine suspended thereby, a main anchor

normally carried by the mine and adapted to drop therefrom to a suspended position for exploding the mine, and a drag anchor controlling the dropping of the main anchor from the mine.

3. A submarine mine comprising a float, a mine suspended therefrom, an anchor flexibly connected with the mine and adapted to drop therefrom, means for normally holding the mine and anchor together, and a drag anchor for releasing the anchor from the mine, the resistance of the water acting against the drag anchor when the float is engaged and dragged by a passing vessel.

4. In a submarine mine, the combination of a float, a mine, a suspended element between the float and mine, an anchor, means for connecting the anchor and mine together and supporting both on only a portion of the said suspending element, means for causing the anchor to drop and hang from the mine and cause the mine and anchor to be suspended by the full length of the suspending element, a firing device, and breakable wires controlling the firing device and connected with the suspending element, the breaking of said wires releasing said firing device to allow it to come into action.

5. A submarine mine comprising a floating cable, an explosive device on the ends thereof and each including firing means, an anchor releasably attached to each device and controlling the operation of the firing means, and means controlled by the dragging of the mines through the water to release the anchors from the said mines.

6. The combination of a floating element, a mine suspended thereby, an anchor, a device for releasably holding the anchor and mine together, means for suspending the anchor from the mine when the anchor is released from the latter, a drag anchor controlling the releasing of said means, said mine including a firing device, and means controlling the operation of the firing device when the anchor becomes suspended from the mine.

7. The combination of a floating element, a mine, a suspending cable between the mine and element, an anchor, a device for releasably holding the anchor and mine together, with the mine disposed on its side, a cable by which the anchor is suspended from the mine when the said device is released, a drag anchor controlling the operation of the said device to release the anchor, the said mine including a firing device, and breakable means between the mine suspending cable and firing device whereby the latter operates by the weight of the mine and anchor being brought to bear on the mine suspending cable.

8. The combination of a floating element, a mine including a firing device, a suspending cable between the mine and element, a

- main anchor, a connecting cable between the mine and anchor, a device for holding the anchor and mine releasably together and engaged with the mine suspending cable 5 to hold a portion of such cable slack, a drag anchor, means on the main anchor for paying out the drag anchor, means between the paying-out means and said device for releasing the latter for permitting the main anchor to be suspended by its cable, and breakable means between the slack portion of the said cable and the firing device whereby the firing device is operated when the weight of the mine and 10 main anchor is brought to bear on the slack portion of the said mine suspending cable.
9. The combination of a mine, a suspending cable, an anchor, a retaining cable for normally holding the mine and anchor together and engaged with the suspending cable to hold a portion thereof normally slack; said mine including a firing device, means controlled by the slack portion of the said cable for operating the firing device, and means for releasing the retaining cable to permit the weight of the mine and anchor to be brought to bear on the slack portion of the suspending cable to cause the firing device to operate.
10. The combination of a mine, an anchor on which the mine normally rests on its side, a device for releasably holding the mine and anchor together and including a lock, a drag anchor, a cable connecting the drag anchor 35 with the first mentioned anchor, means controlled by the said cable for releasing the lock to permit the mine and anchor to separate, a suspending cable for the mine with which the device normally engages to hold a portion of the suspending cable slack, a firing means for the mine, and means between the said firing means and slack portion of the suspending cable whereby the firing means is operated when the said device releases the suspending cable.
11. The combination of a mine, an anchor on which the mine rests on its side, a retaining cable fastened at one side to the mine and engaged with the mine to hold the latter on the anchor, a device for releasably connecting the other end of the retaining cable with the anchor, a drag anchor, a cable connected therewith, means on the first mentioned anchor to pay out the drag 50 anchor, a rotatable element actuated by the paying out means and permitting the said device to open when a predetermined amount of drag cable has been paid out, and a firing device for the mine controlled by the said retaining cable.
12. The combination of a mine, a suspending cable composed of two portions con-

nected by a ring, a main anchor, a retaining cable fastened to the anchor and passing over the mine and through the said ring of the suspending cable to normally hold one portion of the cable slack, a locking bolt on the anchor for releasably engaging the said retaining cable, a firing device for the mine, breakable elements between the slack part of the suspending cable and firing device, an anchor suspending cable connected with the anchor and mine, and means actuated by the dragging of the anchor and mine through the water to release said bolt.

13. The combination of a mine, a suspending cable composed of two portions connected by a ring, a main anchor, a retaining cable fastened to the anchor and passing over the mine and through the said ring of the suspending cable to normally hold one portion of the cable slack, a locking bolt on the anchor for releasably engaging the said retaining cable, a firing device for the mine, breakable elements between the slack part of the suspending cable and firing device, an anchor suspending cable connected with the anchor and mine, a drag anchor, a winding device on the main anchor, a cable connecting the winding device and drag anchor, and means controlled by the winding device for permitting the bolt to release the said retaining cable.

14. The combination of a mine, a suspending cable composed of two portions connected by a ring, a main anchor, a retaining cable fastened to the anchor and passing over the mine and through the said ring of the suspending cable to normally hold one portion of the cable slack, a locking bolt on the anchor for releasably engaging the said retaining cable, a firing device for the mine, breakable elements between the slack part of the suspending cable and firing device, an anchor suspending cable connected with the anchor and mine, a drag anchor, means on the main anchor for normally suspending the drag anchor, a cable connected with the drag anchor, a winding drum on the main anchor from which the drag anchor cable pays out, and a device movable with the drum for permitting the bolt to release the retaining cable when a predetermined length of drag anchor cable has been paid out.

In testimony whereof I have signed my name to this specification in the presence of two subscribing witnesses.

GIOVANNI EMANUELE ELIA.
